ABSTRACT: This auxiliary carburetor comprises a reservoir which is recharged with liquid, in ordinary, nonatomized liquid form, from a recharge tank through check valves. The liquid is expelled, under air pressure, through a dipping tube and a diffuser which atomizes this liquid.

**AUXILIARY COLD-STARTING CARBURETORS FOR
INTERNAL COMBUSTION ENGINES AND FEEDER
TANKS THEREOF**

This invention relates to auxiliary cold-starting carburetors for internal combustion engines and to their feeder tanks.

It is well known that internal combustion engines and especially diesel engines are sometimes difficult to start, particularly in cold weather or after they have not been run for a lengthy period.

It has already been proposed to start such engines by injecting a carbureted mixture which is much more inflammable than the normal working mixture.

The starting mixture is obtained by atomizing a highly inflammable liquid contained in a reservoir built into the starting carburetor, the latter being mounted on the engine support or in proximity thereto.

It is obviously necessary to be able to refill the starting carburetor's reservoir when it is empty.

It is the primary object of the present invention to overcome certain drawbacks and risks that may arise due to the need to transfer the liquid from the feeder tank into the auxiliary carburetor's reservoir.

It is necessary above all for the inflammable liquid or its vapors to be unable to escape or go elsewhere than into the starting carburetor's reservoir, for in the open atmosphere they represent a serious fire if not explosion hazard.

The smell of even minute quantities of such vapors could have inconveniencing effects, moreover.

The starting carburetor's reservoir must also be prevented from being filled with a liquid other than the one for which it was originally designed, otherwise ill-informed users could be tempted to use a liquid which, though cheaper, might be too explosive and therefore detrimental to long engine life.

The present invention includes the main steps:

of enclosing the liquid recharging fuel together with a pressurized expelling gas inside a feeder tank the delivery orifice of which, provided in a union member, is closed by a check valve, said gas being chemically inert with respect to the liquid fuel, notable examples being nitrogen or carbon dioxide, the fuel being expelled in solid form and not as a spray;

of providing a check valve for closing the filling orifice of the reservoir built into the starting carburetor, which orifice is provided in a union member complementary to that of the feeder tank; and

of providing means at the auxiliary carburetor end and/or feeder tank end for opening the feeder tank check valve at least when said feeder tank and carburetor are leak-tightly interconnected, the feeder tank check valve and possibly the open means thereof (in cases where they are provided at the feeder tank end) being mounted in the bottom of the union, in a position recessed from the open end thereof where it is inaccessible for direct manipulation.

The description which follows with reference to the accompanying nonlimitative drawing of a preferred embodiment will give a clear understanding of the manner in which the invention can be carried into practice.

The single FIG. of the accompanying drawing shows, partly in front elevation and partly in axial section, a portion of a starting carburetor and its recharging feeder tank according to the present invention.

Referring to the accompanying drawing, the auxiliary starting carburetor shown thereon comprises a built-in reservoir 1 and a feeder tank for recharging this reservoir 1 with a combustible liquid 2 of guaranteed origin, that is to say that it is difficult to recharge reservoir 1 with any liquid not originating from the feeder tank.

On engine starting, the carburetor draws off from its built-in reservoir 1 a certain quantity of the liquid 2, atomizes it and injects the carbureted mixture thereby obtained through a duct 3 into the engine (not shown).

The recharging liquid is contained together with a pressurized expelling gas in a feeder tank 4 of which the discharge

orifice 5, provided in a union 6, is closed by a check valve 7, said gas being chemically inert with respect to said liquid, examples there of being nitrogen gas or carbon dioxide.

The recharging orifice 8 of reservoir 1 opens into a union 9 complementary to union 6 and is likewise closed by a check valve 10.

Means are provided at the auxiliary carburetor end and/or the feeder tank end for opening at least, the feeder tank check valve, when said tank and the carburetor are leaktightly interconnected.

To this end the auxiliary carburetor union 9 preferably comprises a nipple 11 through which filling orifice 8 opens, the discharge orifice 5 of feeder tank union 6 being ringed by a seal 12 made of an elastomer material which forms a seat for check valve 7 and which, when auxiliary carburetor nipple 11 is driven into orifice 5 and repels check valve 7 whereby to open this valve, encircles nipple 11 so as to form a leaktight joint for transfer of the liquid from feeder tank 4 into reservoir 1, responsive to the pressure of the neutral expelling gas which is contained in feeder tank 4 and which opens check valve 10 by overcoming its countering spring.

In the specific embodiment hereinbefore disclosed and shown in the accompanying drawing, the means for opening feeder tank valve 7 when feeder tank 4 is connected to the auxiliary carburetor are provided on the auxiliary carburetor in the form of a nipple 11.

When feeder tank 4 is separated from the auxiliary carburetor it is thus impossible by direct manipulation to accidentally open its valve 7 mounted on the bottom of union 6, in a position recessed from the orifice 5 thereof.

By way of an alternative embodiment (not shown), part at least of the means referred to may be mounted on feeder tank 4, for instance in the form of a nipple rigid with valve 7, in which case it is necessary in accordance with the present invention to ensure that such means remain in union 6, set back from its orifice 5, i.e. in a position protected from inadvertent direct manipulation liable to cause an accidental discharge under pressure of the highly inflammable liquid (which it is most desirable to keep away from contact with the respiratory organs and the skin).

This averts a risk which could be aggravated by the fact that a feeder tank 4, located for example on board a motor vehicle, could be within reach of a child sitting beside the driver or passengers when they are smoking.

During transfer of the liquid from feeder tank 4, held head downwards, to the reservoir 1 it is clearly essential for the air or vapors contained in reservoir 1, the volume of which is replaced by liquid 2 originating from tank 4 and entering reservoir 1, to be able to escape from the latter. Such air or vapors are accordingly conveyed into a duct which connects with the engine inlet manifold (not shown). Such duct will preferably be the duct 3 referred to precedingly. This avoids any propagation of highly inflammable vapors during recharging of the auxiliary carburetor, such vapors being conveyed into the inlet manifold where they are harmless and serve on the contrary to facilitate the next engine start.

During the atomization phase in the embodiment depicted in the accompanying drawing, reservoir 1 receives air under pressure through a nonreturn valve (not shown), fitted in a tube 13 (leading for instance from a hand-operated piston pump, not shown, or from an electric compressor or any other source of compressed air) and contains a dripping tube 14 which extends down to the bottom of the reservoir and is connected to duct 3 through a diffuser 15 the diffusion chamber 16 of which has one of its ends opening into dripping tube 14 via a nozzle 17. Passages 18, numbering four for example, are formed in diffuser 15, around the nozzle 17. The other end of diffusion chamber 16 communicates with duct 3 via a check valve consisting, say, of a ball 19 applied by a compression spring 20 against its seat, above diffusion chamber 16. When it is open, this valve causes chamber 16 to communicate with duct 3. Alternatively, the seat of valve 19 could be formed by the upper rim of diffuser 15.

In a device as hereinbefore described, when air under pressure is introduced through tube 13 into reservoir 1, this air, the pressure of which is exerted upon the surface of liquid 2, escapes through passages 18 into diffusion chamber 16 and in so doing sustains a pressure loss, the resulting pressure difference causing the liquid 2 contained in reservoir 1 to flow through dipping tube 14 and nozzle 17 and to be atomized and discharged through duct 3 into the engine inlet manifold as valve 19 is raised.

In this particular embodiment, the passages 18 which effect the atomization also serve to allow the air or the vapors of liquid 2 contained in reservoir 1 to escape during the reservoir recharging process, as the liquid 2 is transferred from feeder tank 4 to reservoir 1.

It is necessary, according to the present invention, for the cross-sectional area in the transfer passageway 8 between feeder tank 4 and reservoir 1 to be smaller than the sum of the cross-sectional areas of the passages 18, whereby during recharging of reservoir 1 and irrespective of the pressure under which liquid 2 is transferred from feeder tank 4 to reservoir 1, the air or the vapors of the liquid 2 passing through the passages 18 cannot create, in diffusion chamber 16, a pressure drop in relation to the interior of reservoir 1 capable of causing liquid 2 to be sucked through dipping tube 14 and nozzle 17 and to be atomized before it leaves chamber 16 and reaches the engine inlet manifold through duct 3.

The pressure which holds valve 19 against its seat and which depends upon the rate of spring 20 must obviously be less than the pressure of the expelling gas contained in feeder tank 4, which pressure preferably does not exceed 4 kilograms per square centimeter at 20°C.

Between filler union 9 and reservoir 1, for instance downstream of filler valve 10, is mounted a filter 21 which prevents the ingress of any foreign matter into reservoir 1.

Reservoir 1 is preferably made of a transparent or translucid material in order to enable its filling to be monitored and

stopped when the liquid 2 reaches the required level, which level must in no case reach the inlet openings of passages 18.

I claim:

1. An auxiliary carburetor for starting a cold internal combustion engine which comprises:
a tank for storing liquid fuel;
an inlet means through which said tank can be refilled which comprises a hollow male element provided at the upper portion of said tank which is adapted to operate a valve in a container providing liquid fuel under pressure to refill said auxiliary carburetor and an opening in said male element cooperating with a check valve disposed between said opening and said tank;
a first duct ending in the upper part of said tank to supply air thereto; and
an outlet means through which the fuel and air are directed into the engine disposed on the upper portion of said tank which comprises a duct connected on one end to the engine and the other with a first opening in the upper portion of the tank and further comprising a tube protruding downward into the lower portion of the tank and which is in connection with said duct having at least one bypass opening in said tube communicating with the upper portion of said tank, a check valve being provided in said duct downstream of said bypass opening.
2. An auxiliary carburetor according to claim 1 wherein said opening provided in said elongated male element has an axis transverse to the longitudinal axis of said male element and in which said male element is located in a recess adapted to receive in an interlocking manner said refilling container in order to eliminate any spilling in the refilling operation.
3. An auxiliary carburetor according to claim 1 wherein the cross-sectional area of the opening in said male element is less than the cross-sectional area of the bypass opening.
